UNITED STATES PATENT OFFICE.

RALPH D. MERSHON, OF NEW YORK, N. Y.

PROTECTION OF ELECTRICAL SYSTEMS FROM LIGHTNING AND OTHER STATIC DISTURBANCES.

No. 852,026.

Specification of Letters Patent.

Patented April 30, 1907.

Application filed May 8, 1905. Serial No. 259,329.

To all whom it may concern:

Be it known that I, RALPH D. MERSHON, a citizen of the United States, residing at New York, in the county and State of New York, have invented certain new and useful Improvements in Protection of Electrical Systems from Lightning and other Static Disturbances, of which the following is a specification, reference being had to the drawings accompanying and forming part of the same.

My invention relates to means for protecting electrical systems from the destructive effects of lightning and other static disturbances, and has for its chief object to insure certainty of operation in the devices provided to lead the static discharge to ground.

My invention contemplates the employment of any suitable "arrester", that is, any suitable device or devices containing one or more dielectric gaps across which the static discharge jumps in its path to ground, and relates more particularly to the construction or arrangement, or both, of the external circuit, or that part of the external circuit, to which the "arrester" devices are connected.

The main object of my invention is effected by such construction or arrangement of the external circuit as will, at the point where the arrester is connected thereto, lessen the electro-static capacity of the conductors. This may be secured by diminishing the size of the conductor or conductors in which such result is desired, or by elevating the conductor or conductors for more or less of their length between the arrester and the apparatus to be protected, whereby the capacity to ground is lessened; or by separating the conductors, whereby their capacity relative to each other is lessened. A potential wave traveling along the conductor will, upon reaching the smaller portion of the same, have its potential increased and hence will be more certain to discharge across the gap or gaps provided for that purpose. This result will be aided by elevating the conductors as described, so that they have a greater capacity to ground at the arrester than beyond it. Separating the conductors, to decrease the electro-static capacity between them, is effective only as regards static disturbances, which tend to discharge from one conductor to another.

Another effect of diminishing the size of the conductors as described, is to increase their inductance, so that the conductor is, in a measure, choked between the arrester and the apparatus to be protected, thus putting

greater pressure on the arrester and making a discharge across the gap or gaps still more certain.

Referring now to the drawing for a description of a more convenient embodiment of the invention: Figure 1 is a diagram showing a system in which the conductors of the external circuit are reduced in size between the arresters and the apparatus to be protected. Fig. 2 is a diagram showing the conductors both reduced in size and elevated. Fig. 3 is a diagram showing the conductors reduced in size, elevated and separated. Fig. 4 is a diagram showing a system in which the line conductors are reduced in size at the arrester and of normal size beyond. Fig. 5 is a diagram of a system in which the conductors are reduced, elevated and separated, and also showing the preferred manner of connecting the arresters to the conductors.

Referring now more particularly to Fig. 1: 1, 2, indicate the line conductors of the external circuit, and 3 designates the apparatus to be protected from lightning or other static disturbance. At the point where the arrester devices, illustrated diagrammatically at 4, 5, are to be connected, the conductors are reduced in size, thereby decreasing their capacity and increasing their inductance. The result is that the electro-static wave on reaching the arrester will have its potential raised, causing it to more readily break down the air-gaps and pass thence to ground instead of traversing the reduced part of the conductors on to the apparatus.

In Fig. 2, the aerial conductors 6, 7, are not only reduced at the arrester, but are also elevated beyond the apparatus, thereby reducing the capacity of the conductor to ground, between the arrester and the apparatus, so that the static wave will tend still more to seek the shorter path to ground through the arrester. It will of course be clear that the plan of elevating the conductors may be employed without also reducing their size,—that is, the parts of the conductors which are elevated may be of normal size, Fig. 2 showing merely that the two features may be combined. Likewise, the greater elevation of the conductor or conductors may extend for only a comparatively short distance, being then brought closer to ground, as for example to their original elevation, as shown in Fig. 2.

In Fig. 3 the conductors 8, 9, are reduced, elevated and separated, with the result that,

in addition to the effects secured in Figs. 1 and 2, the capacity of the conductors relative to each other is reduced between the arrester and the apparatus. This arrangement is for the purpose of taking care of static disturbances which tend to discharge across the conductors. Its effect is to make escape through the arresters easier than across the circuit beyond them. The separation of the conductors may extend as far along the circuit as desired, after which they may be brought closer together again, as for example to their original distance apart; as shown in Fig. 3 before reaching the apparatus 3.

In all the above figures the conductors are of reduced size throughout their entire extent from the arrester to the apparatus. It is evident that in all of the arrangements described they may be of normal size beyond the arrester being reduced only for a comparatively short length where the arrester is to be connected. Fig. 4 is introduced merely to give a graphic illustration of this construction, it being understood that the construction holds good for the arrangements shown in Figs. 2 and 4, as well as in Fig. 1. In Fig. 4 the conductors are indicated by 10, 11; the apparatus to be protected and the arrester devices being designated by 3, and 4, 5 respectively, as before.

The systems illustrated in the drawing are all provided with external circuits composed of two conductors each, but it is of course clear that the number is immaterial and that the circuit may consist of one, two or more, so far as the applicability of my invention is concerned. The arrester devices are preferably connected to the reduced portion of the conductor, but may of course be connected thereto at a point where it is of normal size. That is to say, the reduced, elevated or separated part of the circuit may be wholly or only partly between the arrester and the apparatus to be protected. It is also evident that the features of my invention, namely, the diminishing of the electro-static capacity of the conductor or conductors, by reducing their size, elevating, or separating them, may be used separately, or combined.

Another feature of great value, which may be used separately or in combination with other features of the invention, is shown in Fig. 5. In connecting arresters to the conductor it is customary to carry a lead laterally therefrom to the arrester, which is located a safe distance away. The inductance of this lead is a disadvantage, as it chokes the path to the arrester. The angle which the lead makes with the conductor is also objectionable, since the potential wave must turn a corner to reach the arrester, whereas it will tend to follow the straight path along the conductor. I therefore propose to carry the conductor over to or as near to the arrester

as desired, as indicated in Fig. 5. By this means there is less inductance between the arrester and the conductor. I also may arrange the arrester lead in line with the lateral extension 12 of the conductor, so that the potential wave can go on in a straight path in the direction of the arrester, but must turn an angle to proceed along the conductor. This feature of my invention therefore consists, broadly stated, in carrying the conductor to the arrester; and, if desired, in connecting the arrester in such manner that the potential wave will be able to leave the conductor without turning an angle.

What I claim is:

1. The combination of electrical apparatus; a line conductor connected therewith, a portion of the conductor being of diminished electrostatic capacity; and one or more arrester devices connected to the conductor 85 and to ground; the portion of the conductor having diminished electrostatic capacity being located between the arrester device or devices and the apparatus; as set forth.

2. The combination of electrical apparatus; a line conductor connected therewith, reduced in size for a portion of its length; and one or more arrester devices connected to the conductor and to ground; the reduced portion of the conductor being located between 95 the arrester device or devices and the apparatus; as set forth.

3. The combination of electrical apparatus; an aerial line conductor connected therewith; a portion of the conductor being elevated from the ground higher than the normal distance therefrom; and one or more arrester devices connected to the conductor and to ground; the said elevated portion of the conductor being located between the arrester device or devices and the apparatus; as set forth.

4. The combination of electrical apparatus; an aerial line conductor connected therewith, a portion of the conductor being reduced in size and elevated from the ground higher than the normal distance therefrom; and one or more arrester devices connected to the conductor and to ground; the said elevated and reduced portion of the conductor 115 being located between the arrester device or devices and the apparatus, as set forth.

5. The combination of electrical apparatus; a plurality of conductors connected therewith constituting a circuit, said conductors for a portion of their extent being separated more than their normal distance apart; and one or more arrester devices connected to one or more of the conductors and to ground; the said separated portion of the 120 circuit being located between the arrester device or devices and the apparatus; as set forth.

6. The combination of electrical apparatus; a plurality of conductors connected 130

therewith constituting a circuit, said conductors for a portion of their extent being separated more than their normal distance apart, and one or more of the conductors being reduced in size at said separated portion of the circuit; and one or more arrester devices connected to one or more of the conductors and to ground; the separated portion of the circuit being located between the arrester devices and the apparatus, as set forth.

7. The combination of electrical apparatus; a plurality of aerial conductors connected therewith constituting a circuit, said conductors for a portion of their extent being separated more than their normal distance apart and elevated above the ground more than their normal distance therefrom; and one or more arrester devices connected to one or more of the conductors and to ground; the said separated and elevated portion of the circuit being located between the arrester

device or devices and the apparatus, as set forth.

8. The combination of electrical apparatus; a plurality of aerial conductors connected therewith constituting a circuit, said conductors for a portion of their extent being separated more than their normal distance apart and elevated more than their normal distance above the ground, one or more of the conductors being reduced in size at said separated and elevated portion of the circuit; and one or more arrester devices connected to one or more of the conductors and to ground; the said separated, elevated and reduced part of the circuit being located between the arrester device or devices and the apparatus; as set forth.
